UNITED STATES PATENT OFFICE.

HERBERT C. PETERMAN, OF PHILADELPHIA, PENNSYLVANIA.

BOTTLE CRATE.

Application filed January 12, 1922. Serial No. 528,596.

To all whom it may concern:

Be it known that I, HERBERT C. PETERMAN, a citizen of the United States, residing at Philadelphia, in the county of Philadelphia and State of Pennsylvania, have invented new and useful Improvements in a Bottle Crate, of which the following is a specification.

My invention relates to new and useful improvements in a bottle crate, and has for its object to so construct the crate that the same will be strong and durable although light and relatively simple in construction.

Another object of the invention is to so arrange the partition strips that they will be securely fastened or locked together without the use of independent elements or fastening devices.

Another object of the invention is to provide an improved means for securing the partition strips in place.

Another object of the invention is to provide partition strips having reduced portions adjacent their ends to form necks which are engaged by staples driven into the crate frame in such manner that the partition strips will be securely and firmly held in place.

A further object of the invention is to arrange the longitudinal support or bottom strips in pairs which are locked by the transverse bottom strips so that the longitudinal strips will be positively held in their spaced relation.

A still further object of the invention is to provide for the introduction and maintenance of the intermediate partition strips without the use of fastening devices.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:

Fig. 1, is a perspective view of a bottle crate embodying my invention.

Fig. 2, is a fragmentary perspective view thereof showing the bottom or supporting strips and the intermediate partition strips next above said bottom strips.

Fig. 3, is a fragmentary sectional view of Fig. 2 at about the line 3—3 of said Fig. 2.

Fig. 4, is an enlarged bottom plan view of the bottle crate.

Fig. 5, is an enlarged plan view of one end of one of the partition strips showing the manner of forming the restricted portion or neck.

Fig. 6, is a fragmentary sectional view of the crate frame illustrating the manner of fastening some of the strips, the end portion of one of which is shown in side elevation.

Fig. 7, is a perspective view of one of the partition structures.

In carrying out my invention as here embodied, 2 and 3 represent the end walls of the crate frame while 4 and 5 designate the side walls thereof. The side walls may consist of any suitable material, although they are preferably made of wood, each side end being produced from a single strip or from a plurality of strips depending upon the desires of the manufacturer or the utility that may be obtained from the use of either arrangement. The lower edges of the end walls terminate short of the lower edges of the side walls and after the bottom support structure is positioned filler strips 6 are secured to the lower edges of said end walls.

The reference numerals 7 and 8 represent the pair of associated longitudinal bottom supporting strips which are formed of flat strips of sheet metal with their ends twisted so that said ends occupy a horizontal position while the intermediate portions occupy a vertical position so as to present their edges to the bottles or other objects to be supported and as these crates are particularly adapted for holding milk bottles to be transported and otherwise handled the strips of each associated or coacting pair are spaced a distance less than the diameter of a milk bottle mouth so that such bottles may be supported in an inverted position as well as in an upright position. This is essential because at the present time milk bottles are being washed and sterilized while in the crates in inverted positions. The horizontal end portions of these strips rest upon the lower edges of the end walls and are secured in place by suitable fastening devices 9, such as nails passing through the ends of the strips and into the end walls which are afterwards covered with the filler strips which are also held in place by suit-

able fastening devices passing through the filler strips and into the end walls between the metal strips of the bottom supporting structure, the positions of the last named fastening devices being represented by the holes 10 in one of the end walls of Fig. 4. In lieu of this manner of fastening the metal strips the fastening devices may first pass through the filler strips and then through the ends of the metal strips 7 and 8 into the end walls. In order to make a much neater job either of the lower edges of the end walls or the upper edges of the filler strips may be notched to provide sockets for the ends of the metal supporting strips 7 and 8.

Associated with the longitudinal strips 7 and 8 are the transverse strips 11 any number of which may be used according to the strength and rigidity required or desired. These transverse strips pass through slots 12 in the longitudinal strips and their ends twisted for insertion in the recesses 13 in the side walls of the crate frame, as plainly shown in Fig. 1. These transverse strips are inserted in the recesses prior to the ends of the longitudinal strips being fixed in place and while the entire length of said strips occupy a horizontal position so that this bottom support and structure may be bowed sufficiently to permit the insertion of the ends of said transverse strips in said recesses.

The transverse strips preferably have cut-away portions 14 adjacent each end to form a restricted neck 15 thereby producing a head 16 and shoulders 17 and this neck portion is straddled by a staple 18, as the fastening device, which engages the shoulder 17 when driven diagonally into the side members of the crate frame. By this means the secure attachment of said strips to the crate frame is insured. After all of the strips of the bottom supporting structure are properly secured the portions of the transverse strips between the sides of the crate frame and the different longitudinal strips are twisted so that said intermediate portions lie in a vertical position while the portions at the extreme ends and at the crossing points where the transverse strips pass through the longitudinal strips, occupy a vertical position as may be plainly conceived by reference to Fig. 7. By this arrangement the different strips are securely locked together thus absolutely preventing said strips from becoming accidentally displaced or forced apart and this is particularly essential in the lower supporting structure for if the longitudinal strips which are associated in pairs were permitted to separate the bottles when in inverted positions might stick through the supporting structure and be broken or cause damage to the bottle washing machinery.

Above the bottom supporting structure are

arranged a number of partition structures each of which consists of a number of longitudinal strips 19 so located with relation to the pairs of longitudinal strips of the bottom supporting structure as to lie in a vertical plane intermediate adjacent pairs of the longitudinal strips of said bottom supporting structure as may be plainly ascertained by reference to Figs. 2 and 4. These strips are constructed in the same manner as described with relation to the strips 7 and 8 and have the transverse strips 20 passing through slots 12 in said longitudinal strips and having their intermediate portions twisted so that their points of crossing and their ends occupy horizontal positions, while said intermediate portions occupy vertical positions. These transverse strips are spaced a sufficient distance to permit the insertion of a bottle therebetween which is also true of the longitudinal strips 19.

The ends of all the strips of the uppermost partition structure are preferably formed as shown in Fig. 5 and inserted in recesses in the end and side walls of the crate frame and then fastened as described and shown in Fig. 6, but the intermediate partition structures after being positioned by inserting the ends in the recesses formed in the walls of the crate need not be secured by fastening means since the twisting of the transverse strips securely lock the different strips together, thus preventing them from being bowed in any direction to overcome the possibility of the ends being withdrawn from the recesses.

I am aware that similar strips have been before used in bottle crates of this character but they have not been locked together by passing certain strips through others and then twisting them to make a locking structure without needing any additional fastening means at their points of crossing, neither am I aware that any one has constructed the ends of the strips so as to provide restricted necks and shoulders which are engaged by staples driven diagonally in the crate frame for holding the different structures.

Of course I do not wish to be limited to the exact details of construction as herein shown as these may be varied within the limits of the appended claims without departing from the spirit of my invention.

Having thus fully described my invention, what I claim as new and useful is:

1. A bottle crate comprising a frame, and a bottle supporting structure including longitudinal flat metal strips fixed to the frame in spaced relation, and transverse strips passing through the longitudinal strips and fixed to the frame, said transverse strips having the portions intermediate the longitudinal strips twisted so that said intermediate portions occupy vertical positions while the ends and crossing portions

120

125

130

- occupy horizontal positions thereby locking the different strips together.
2. A bottle crate comprising a frame, and partition structures each consisting of longitudinal flat metal strips provided with slots and having their ends twisted so as to occupy horizontal positions with the major or intervening portions occupying vertical positions, the ends of said strips being inserted in recesses in the frame, and transverse flat metal strips passing through the slots in the longitudinal strips with their ends inserted in recesses in the frame, said transverse strips having the portions intermediate the longitudinal strips, as well as between the strips and frame, twisted so as to occupy vertical positions while the portions at the points of crossing and the ends occupy horizontal positions, the ends of certain of said strips having restricted neck portions to produce heads with shoulders and staples straddling the restricted neck portions and driven diagonally into the frame so as to engage the shoulders for securing the parts together.
3. A bottle crate comprising a frame and a bottle supporting structure including a plurality of strips fixed to the frame, other strips passing through the first named strips and fixed to the frame and means for locking the strips together to prevent displacement of one set of strips from the other set.
4. A bottle crate comprising a frame and a bottle supporting structure including a plurality of flat metal strips fixed to the frame, said strips having slots therein and other strips passing through the slots in the first named strips and fixed to the frame.
5. A bottle crate comprising a frame and a bottle supporting structure including a plurality of flat metal strips fixed to the frame, said strips having slots therein and other strips passing through the slots in the first named strips and so bent as to lock all the strips against displacement relative to each other, said other strips also being fixed to the frame.
6. A bottle crate comprising a frame and a bottle supporting structure including flat metal strips having restricted neck portions adjacent their ends to produce heads with shoulders, said heads being inserted in the walls of the frame and staples straddling the restricted neck portions and driven diagonally into the frame so as to engage the shoulders for securing the strips to the frame.
7. A bottle crate including a partition member in the form of a flat metal strip having a restricted neck portion adjacent an end thereof to produce a head and shoulders.

In testimony whereof, I have hereunto affixed my signature.

HERBERT C. PETERMAN.
